TRUSTEE, OF NEW YORK, N. Y.

PULP-BOTTLE MACHINE.

1,137,669.

Specification of Letters Patent. Patented Apr. 27, 1915.

Application filed April 16, 1913. Serial No. 761,511.

To all whom it may concern:

Be it known that I, ERICH SCHINSCHOLL, a subject of the Emperor of Germany, and a resident of Ashland, in the county of 5 Grafton and State of New Hampshire, have invented certain new and useful Improvements in Pulp-Bottle Machines, of which the following is a specification.

This invention relates to machines for 10 making bottles and other receptacles from paper pulp and the like.

The object of my improvements is to provide a machine of the class specified simple in construction and reliable and rapid in 15 operation.

With these ends in view my improvements comprise means illustrated in their preferred form in the drawings accompanying this specification, wherein—

20 Figure 1 is a vertical section of so much of a bottle machine as is necessary to illustrate my improvements. Figs. 2, 3 and 4 are fragmentary sectional elevations similar to a portion of what is shown in Fig. 1 and illustrating steps in the operation of 25 my improved machine. Figs. 5 and 6 are respectively an elevation and a bottom plan view of a detail of my machine. Fig. 7 is a vertical section on line 7, 7 of Fig. 6 and 30 Fig. 8 is a cross section on line 8, 8 of Fig. 5. Fig. 9 is a side view of a detail of my improvements illustrating a modification thereof. Figs. 2 to 4 inclusive are to one scale, smaller than that of Fig. 1. Figs. 5 to 9 inclusive are to one scale, larger than 35 that of Fig. 1.

Before describing the invention in detail I desire to have it understood that the invention is not limited to the particular construction and arrangement of parts which I have illustrated and shall hereinafter describe, and that various changes may be made in the mechanism without departing from the spirit or scope of the invention, 45 and that the phraseology which I employ is for the purpose of description and not of limitation.

My improved machine comprises pulp cylinder 2 slidably mounted in fixed bracket 3. Said bracket may be provided with pulp delivery pipe 4 leading from some source of supply not shown. Cylinder 2 has pulp inlet 5 on that side adjacent to the delivery end of pipe 4. Piston 6 is slidably mounted

in cylinder 2 and stem 9 thereof may project upwardly out from cylinder 2. 55

Cylinder 2 and piston 6 may be reciprocated by hand or some suitable automatic mechanism, not shown but well known in the mechanical arts may be supplied for 60 those purposes. Hollow mold 10 may be of well known construction such as woven wire net 11 whose inner face is formed in the desired shape of the outside of the finished bottle or other receptacle which it is desired 65 to form. Said net may be in two or more sections which may be conveniently clamped together by flanges as 12. Said mold may be provided with a downwardly reaching stem 13 for engagement with hole 14 in table 70 15 for supporting said mold. Said table is preferably supported for rotation in bearing 16 of rotatable frame 17 pivotally mounted on vertical shaft 18. Said table 15 is preferably provided with pinion 19 for 75 engagement with gear 20 concentrically mounted with frame 17, whereby successive molds as 10 may be successively presented to filling position relatively to the filling mechanism, comprising cylinder 2 and piston 6. 80

Fixed to and depending from the lower end of cylinder 2 is distributing tube 21 comprising cylindrical side wall 22 and bottom 23. Said side wall and bottom may be 85 provided with suitable discharge openings as slots 24 or holes 25, and I preferably graduate or proportion the size of those openings, corresponding with the desired amount of material to be delivered there- 90 through, in accordance with the contour of the article to be formed. For instance, as illustrated, the body portion 27 of pulp bottle 26 being of greater diameter than neck 28 thereof slot 24 will be of greater width 95 in its lower part than in its upper part, and the extreme top 29 of said slot will be enlarged to provide adequate delivery of pulp for forming the flange 30 at the mouth of said bottle. Or for instance, in the modification of Fig. 9, those holes 25 near the lower end of tube 21 will be larger than the holes farther up therein. There is thus provided a graduated delivery commensurate with the result desired. As a further guide 100 to uniform circumferential distribution I provide within said tube 21 distributing stem 31 having lengthwise slots as 32 there-

in, arranged opposite and in communication with the discharge openings in said tube respectively. This stem fills said tube except for the spaces provided by said slots, and which slots form delivery channels from chamber 34 of cylinder 2 to discharge openings 24 or 25 of tube 21. Thus by rotating frame 17, mold 10 may be moved from and to filling position and vice versa. Also by rotating gear 20 said mold may be caused to rotate on its own axis at such speed as to centrifugally force the fluid pulp against the inner wall of said mold 10. While it will be obvious that frame 17 and gear 20 may be suitably rotated by hand, those members will preferably be rotated as desired by suitable automatic means well known in the mechanical arts, but omitted herein as extraneous to the subject matter of the present invention. It will also be obvious to those skilled in the art that other tables rotatably mounted in brackets, similar to table 15 and bracket 16, may be arranged symmetrically about the outer portion of frame 17. Said slots as 32 may be equal in number with slots 24 or lengthwise rows of holes as 25 but I have found that one slot 32 in stem 31 may efficiently serve at least two of slots 24 in tube 21 as illustrated.

The operation of my improved mechanism is as follows: Mold 10 having been assembled and placed in position on table 15 and that table having been brought into receiving position in line with cylinder 2 by suitable rotation of frame 17, gear 20 is rotated thus rotating table 15 and mold 10 thereon. Cylinder 2 is then moved upwardly to receiving position with piston 6 above inlet 4 as shown in Fig. 2. Pulp 40 is then injected through pipe 4 and inlet 5 to chamber 34 of said cylinder, below piston 6 until that chamber is filled. It will be obvious that the capacity of said chamber may be changed by changing the upper position of piston 6 relatively to the bottom of cylinder 2 whereby bottles of different thickness of wall may be formed. After said cylinder chamber 34 is filled said cylinder and piston are moved downwardly in unison until distributing tube 21 has entered mold 10 a suitable distance and until cylinder bottom 33 engages and closes the top of mold 10, Fig. 3. Thereupon piston 6 is forced downwardly, ejecting the fluid pulp through slots 32 and through slots 24 or holes 25 against the interior face of the rapidly rotating mold 10, Fig. 1. The pressure from piston 6 will force the pulp against said mold and the centrifugal force due to rotation of said mold will further tend to pack the pulp against the walls of the mold while said rotation will also tend to distribute the pulp equally circumferentially. Said mold being of net or otherwise perforated the fluid in which the pulp is

suspended will be forced outwardly therethrough. After piston 6 has descended to the bottom of cylinder 2, near which bottom it is shown in Fig. 1, cylinder 2 may be retracted, and after tube 21 is partly withdrawn, piston 6 may be retracted in said cylinder, Fig. 4, and the parts eventually be restored to the position of Fig. 2. Then frame 17 may be rotated to move filled mold 10 from under cylinder 2, for removal and replacement by an empty mold. Said filled mold may then be taken apart and the formed bottle removed for drying.

I claim:

1. In a machine of the class specified the combination of a mold, a distributing tube having discharge openings therein, said openings varying in size relatively to the size of that portion of the mold opposite thereto respectively, and means for supplying liquid pulp to said tube. 80
2. In a machine of the class specified the combination of a mold, a distributing tube having discharge openings therein, a distributing stem within said tube, said stem being provided with delivery channels opposite said discharge openings in the tube, and means for supplying liquid pulp to said tube. 90
3. In a machine of the class specified the combination of a pulp chamber, a mold, a distributing tube, and a distributing stem within said tube, said stem being provided with delivery channels connecting the pulp chamber with the discharge openings in said tube. 95
4. In a machine of the class specified the combination of a pulp chamber, a mold, a distributing tube, discharge openings in said tube, the sizes of said openings being proportionate to the contour of said mold, and a distributing stem within said tube, said stem being provided with delivery channels connecting the pulp chamber with the discharge openings in said tube. 105
5. In a machine of the class specified the combination of a pulp chamber having a distributing tube fixed thereto, discharge openings in said tube, a piston in said chamber, a rotatable mold, means for moving said chamber for causing said tube to enter said mold, and means for moving said piston relatively to said chamber. 110
6. In a machine of the class specified the combination of a pulp chamber having a distributing tube fixed thereto, a piston in said chamber, a mold, means for moving said chamber for causing said tube to enter said mold and means for moving said piston relatively to said chamber; discharge openings in said tube, said openings varying in size relatively to the size of that portion of the mold opposite thereto respectively. 120
7. In a machine of the class specified the combination of a pulp chamber having a 130

- distributing tube fixed thereto, a piston in said chamber, a mold, means for moving said chamber for causing said tube to enter said mold, means for moving said piston relatively to said chamber, discharge openings in said tube, the sizes of said openings being proportionate to the contour of said mold, and a distributing stem within said tube, said stem being provided with delivery channels opposite said discharge openings in the tube.
8. In a machine of the class specified the combination of a rotatable mold, a distributing tube, discharge openings in said tube, the sizes of said openings being proportionate to the contour of said mold, means for rotating said mold, and means for moving said mold into and out of receiving position relatively to said tube.
9. In a machine of the class specified the combination of a rotatable mold, a distributing tube, discharge openings in said tube, a distributing stem within said tube, said stem being provided with delivery channels opposite said discharge openings in the tube,
- means for rotating said mold, and means for moving said mold into and out of receiving position relatively to said tube.
10. In a machine of the class specified the combination of a rotatable mold, a pulp chamber, a distributing tube fixed thereto, discharge openings in said tube, said openings varying in size relatively to the size of that portion of the mold opposite thereto respectively, a distributing stem within said tube, said stem being provided with delivery channels connecting the pulp chamber with the discharge openings in said tube, means for rotating said mold, and means for moving said mold into and out of receiving position relatively to said tube.

Signed at Ashland, in the county of Grafton and State of New Hampshire, this 14 day of April, 1913, before two subscribing witnesses.
